UNITED STATES PATENT OFFICE.

SIMON LAKE, OF BALTIMORE, MARYLAND, ASSIGNOR TO THE LAKE CAPPING MACHINE COMPANY, OF NEW YORK, N. Y.

CAN-CAPPING MACHINE.

SPECIFICATION forming part of Letters Patent No. 427,332, dated May 6, 1890.

Application filed August 22, 1889. Serial No. 321,668. (No model.)

To all whom it may concern:

Be it known that I, SIMON LAKE, of Baltimore, in the State of Maryland, have invented a new and useful Improvement in Can-Capping Machines, of which the following is a full, clear, and exact description.

My invention relates to a can-capping machine, and has for its object to provide a machine so constructed that when in operation the cans will be fed to place, the caps held thereon, the solder cut and delivered to the irons, and the irons distribute the solder along the margin of the cap and the surface of the can with which it contacts.

15 A further object of the invention is to provide a machine of simple and durable construction, whereby the operation of capping will be greatly facilitated and the labor reduced to a minimum.

20 Another object of the invention is to apply a gasoline-flame to the irons, whereby the said irons are effectually and economically heated.

The invention consists in the novel construction and combination of the several parts, 25 as will be hereinafter fully set forth, and pointed out in the claims.

Reference is to be had to the accompanying drawings, forming a part of this specification, 30 in which similar letters and figures of reference indicate corresponding parts in all the views.

Figure 1 is a front elevation of the machine, partly in section. Fig. 2 is a central vertical section. Fig. 3 is an end view, a portion 35 of the treadle being broken away. Fig. 4 is a partial plan view of the machine. Fig. 5 is a side elevation of the levers acting in conjunction with the treadle, and Fig. 6 is a partial side elevation of one of the knives used 40 in the machine.

The frame of the machine is preferably attached to a skeleton base 10, and consists, 45 usually, of two parallel perpendicular end pieces 11, connected at or near the center by a longitudinal brace 12, comprising a horizontal plate having the sides and ends upwardly flanged and provided with a series of longitudinally-arranged, preferably circular, openings 50 13, each of the said openings being sur-

rounded by a boss 14, as best shown in Fig. 1. Above the brace 12 a second parallel and similarly-constructed brace 15 is located, and a third brace 16 is attached to the end pieces of the frame above the intermediate brace 15, 55 differing from the others only in that the flanges extend downward and the boss is omitted around the openings.

The openings 13 in the several braces 12, 15, and 16 are in vertical alignment, and in each of said openings a tubular soldering-iron 17 is loosely introduced and capable of revolving, which soldering-irons, extending vertically upward, terminate preferably flush with the upper surface of the top brace 16, 60 their lower extremities being carried below the first or lower brace 12, as illustrated in Figs. 1 and 3. These soldering-irons are preferably constructed in two sections A and A', the lower section being the thicker, and screwed 70 or otherwise attached to the upper section; and the bottom of the lower section A' of each soldering-iron, which distributes the solder, is made somewhat V-shaped or beveled to correspond essentially to the depression made in 75 the tops of the cans around the opening to be capped, which depressions are clearly shown at 18 in Fig. 1. It will be observed that, by reason of the location of the openings in the braces of the frame, the soldering-irons 80 are arranged in two parallel rows, one at each side of the center of the frame.

Within each soldering-iron a perpendicular concentric tube 19 is placed, and the upper end of each of the tubes is inserted and secured in apertures produced in longitudinal bars 20, attached to the end pieces of the frame above the upper brace, as best shown in Fig. 2. The lower ends of the tubes 19 are flaring or conical, as illustrated at 21 in Fig. 90 1, and the body of the tubes is of such diameter that quite a space 22 will intervene the latter and the inner walls of the soldering-irons, which space is greatly diminished at the bottom of the irons by reason of the conical form of the lower ends of the tubes. The tubes 19 terminate at the bottom, essentially flush with the lower end of the soldering-iron section A'.

In each tube 19 a clamping-arm 23 is held 95

to slide vertically, being provided at the upper end, which extends beyond the bar 20, to which the tube 19 is secured, with a weight 24, preferably spherical in form. The lower 5 end of the clamping-arm projects downward beyond the lower portion of the soldering-iron, and the said lower extremity of the clamping-arm is preferably bifurcated, as illustrated in Fig. 1. The bifurcated ends of 10 the clamping-arms are adapted for contact with the caps to hold the same in position upon the top of the cans to receive the solder. The bifurcation is made at the lower extremity of the clamping-arms in order that the 15 vent usually produced in the cap may be uncovered during the process of soldering.

Each soldering-iron has attached to its upper section A a gear-wheel 25, and the gears of each soldering-iron upon each side of the 20 machine are made to mesh, the gears being preferably located between the upper braces 15 and 16.

The soldering-irons are adapted to have a rotary movement, and to that end a drive-shaft 26 is journaled in suitable bearings upon the end pieces of the frame, extending centrally and longitudinally over the same, which drive-shaft is provided with any suitable form of drive-pulley 27, and at or near 25 its center with a bevel-pinion 28. This bevel-pinion 28 meshes with a horizontally-located similar pinion 29, secured to the upper end of a short perpendicular shaft 30, which shaft is journaled in the upper brace 16 at or near 30 the center of the same, as illustrated in Fig. 2, and projects beneath the said brace, having attached to its lower end a spur-wheel 31, which spur-wheel meshes with the opposed pinions of two opposite centrally-located soldering-irons, whereby, through the medium 35 of the drive-shaft, the perpendicular shaft 30, the train of gear-wheels 25, and the intermediate gear 31, a simultaneous rotary movement is imparted to each of the soldering-irons.

Upon the skeleton base 10 of the machine a table 32 is placed, adapted to slide vertically upward in suitable guideways, as shown in Fig. 1. This table has preferably produced 50 upon its upper face ribs 33, adapted to enter correspondingly-located grooves 34, produced in the bottom of a tray 35, in the upper face of which tray a series of depressions or cavities 36 are formed, and in said cavities the 55 cans 38 to be capped are placed. The cavities containing the cans are so located in the tray that when the said tray is placed in position upon the table 32 a can will be immediately beneath each of the soldering-irons of 60 the machine, the center of the can being in perpendicular alignment, or essentially so, with the central longitudinal axis of the iron above it.

To the table 32 a plunger rod or bar 39 is 65 secured, which rod or plunger passes through the skeleton frame to a pivotal connection with the treadle 39^a, fulcrumed in a standard

40, secured to the floor or other support upon which the base 10 rests. At each side of the standard 40 a standard 41 is secured to the 70 floor, and upon each of the said standards 41 a lever 42 is fulcrumed at or near its outer end, the inner ends of which levers contact with pins 43 upon the plunger, as shown in Fig. 5, and the inner ends of the levers 42 are 75 normally held in contact with these pins by springs 44, attached to the levers and to a support beneath the same. The springs are located near the inner end, as is likewise best shown in Fig. 5.

At each side of the end pieces 11 of the frame, at or near the top thereof, the ends of two guide-rollers 45 and 46 are journaled. The upper roller 45, located upon the front of the machine, projects beyond the left side 85 piece and has secured thereto a ratchet-wheel 47, and one end of a link-lever 48 is pivoted to the outer extremity of the roller-shaft, the other end of the link-lever being pivotally attached to a connecting-rod or pitman 49, 90 which is carried downward through the table 32 and base 10, the said rod being provided with a collar 50 above the table, and a coiled spring 51, encircling its lower end beneath the base, which spring is securely held in contact with the rod at its lower extremity and bears against the under face of the base at the upper end, as shown in Figs. 1 and 3. The tendency of the spring 51 is to draw the connecting-rod downward; but its downward 95 movement is limited by the collar 50 contacting with the table 32.

The link-lever 48 has pivoted near the under side a dog 52, which contacts with the teeth of the ratchet-wheel 47, and is held in 105 such contact preferably through the medium of a spring 53, attached to the ratchet and bearing against or upon the dog, as is clearly shown in Fig. 3, whereupon, as the table 32 is forced upward, the connecting-rod 49 is 110 carried upward with the table and the dog is forced to act upon the ratchet-wheel to revolve the same, thereby communicating motion to the guide-rollers 45 and 46.

The guide-rollers at the back of the machine are revolved through the medium of a similar dog and ratchet, preferably attached to the right-hand extremity of the upper roller-shaft, whereby the connecting-rods 49 of the opposed guide-rollers are located at opposite ends of the machine, as shown in Fig. 1. This construction, however, may be altered, if found desirable, without departing from the spirit of the invention.

Longitudinal ribs 54 are formed upon the 125 upper surface of the upper brace 16, one near the front edge and one near the rear edge, as illustrated in Fig. 2, which ribs extend from end to end of the machine, and in front of the inner face of each rib 54, close thereto, a 130 vertical slot 55 is formed in the end pieces of the frame. Parallel, and virtually in contact with the inner face of each rib, a knife 56 is located, the ends of the knives being

carried through or held to slide in the slots 55 of the end pieces, the said slots being so located that when the knives are vertically reciprocated they will essentially slide in contact with the inner faces of the ribs 54, which are smooth and perpendicular. These knives are actuated through the medium of the treadle-levers 42, and a connection is established between the outer extremities of said levers and the outer ends of said knives through the medium of rods 57, as illustrated in Figs. 2 and 3.

When the treadle-levers 42 are in their normal position, which is at a right angle to the plunger 39, as shown in Fig. 5, the knives 56 are in the upper ends of their slots 55.

From each side face of the upper brace 16 brackets 57^a are outwardly and upwardly projected, and in the brackets reels 58 are journaled, upon which wire-solder is wound, the said reels being so located that one is opposite each soldering-iron. Upon the inner face of the brackets 57^a a guide 59 is secured, having a series of apertures 60 produced therein, and opposite each of said apertures 60 an aperture 61 is formed in the ribs 54. The solder is passed from the reels through apertures in the guide-rods, thence between the guide or friction rollers 45 and 46, and out 30 through the apertures in the ribs 54 in the path of the knives 56.

At any suitable point above the machine a tank containing gasoline is placed, connected by a tube 62 with a generating-pipe 63, extending from end to end of the machine between the rows of soldering-irons, the connection between the generating-pipe and the tank being preferably made at or near the center of the former, as shown in Fig. 1. The generating-pipe 63 is filled, as is customary, with wire, representing a net-work in cross-section, to vaporize the gasoline, and at each end of the pipe an elbow 64 is attached, provided at the lower end with a valve 65, whereby the supply of vapor may be cut off at any time. The lower ends of the elbows are preferably located outside the frame.

Beneath the generating-pipe a burner 66 is located between the lower sections A' of the soldering-irons. This burner consists of a tube of a suitable diameter supported in the ends of the frames and provided with a series of peripheral punctures or perforations opposite each soldering-iron, and an interior perforated plate, as best shown in Fig. 2, and into the ends of the tube a smaller concentric pipe 67 is entered, (shown in dotted lines in Fig. 1,) the outer end of which pipe projects through the end of the frame and the inner portion extends some distance within the main-burner tube. The lower ends of the elbows are in horizontal alignment with the outer end of the pipe 67, and between the two a space intervenes. The pipe 67 constitutes a mixing-chamber, as when the valve 65 is opened the air and gasoline-vapors pass together into the pipe 67 and in a commingled

state from the said pipe into the body of the burner. Thus, by lighting the vapor at the perforations of the latter a spray-flame is obtained, which impinges upon the soldering-irons, as shown in Fig. 2. In order to prevent the upper portion of the soldering-irons from becoming heated, asbestos or a similar non-heat conductor is packed upon the brace 75 12 between its flanges and the bosses, as illustrated at 68 in Figs. 1 and 2.

The knives 56 preferably consist of a bar of metal, having the lower edges chamfered or recessed, as illustrated at 69 in Fig. 6, to 80 form a cutting-edge opposite each aperture in the ribs 54, through which the solder passes.

In operation, the drive-shaft 26 having been set in motion, each of the soldering-irons is caused to revolve, and the gasoline-vapor 85 having been turned on and lighted at the burner the lower sections A' of the soldering-irons are quickly and effectually heated. The treadle is first pressed down by the operator, if the machine has not been used, 90 which forces up the table 32 and draws down the knives 56. The connecting-rods 49 are forced upward by the table, and the ratchets 52 are carried upward in contact with the teeth of the ratchet-wheels 47 a sufficient distance to revolve said wheels upon the return movement of the table to unreel the solder. The return movement of the table is accomplished by lifting the foot from the treadle, whereupon the table drops. The springs 44 100 act to draw the treadle-levers 42 to their normal position, carrying the knives to their normal position; and the springs 51 upon the connecting-rods also act to draw said connecting-rods downward, whereupon the dog 105 52 forces the ratchet-wheel to revolve, which sets in motion the friction or guide rollers 45 and 46, and the solder, which has been passed through said rollers and through the apertures in the ribs 54, is fed forward a sufficient distance beyond the ribs to fall, when severed, into the upper end of the soldering-iron. A strip of solder being now in position to be cut, the cans are placed upon their tray and the tray placed in position upon the table 32, the clamping-arms being located over the caps of the cans. The operator now presses upon the treadle 39^a, and each and every can-cap by the upward movement of the table is made to contact with the clamping-arms above them, and the lower ends of the soldering-irons, which are rapidly revolved, are seated in the soldering-channels 110 18. The same movement of the treadle draws down the treadle-levers 42, which movement 115 of the treadle-levers causes the knives to descend and sever the solder, which drops into the space 22 intervening the body of the soldering-iron and the inner tube-casing 19. As the solder passes down this space 22 and 120 reaches the lower or contacted portion of it, it is melted and passes from the soldering-iron in a melted state in sufficient quantities 125 to be evenly distributed over the contacting

surfaces of the cap and can in the channels 18. The treadle is then released, the table drops, the caps having been soldered upon the cans, the knife returns to its normal position, and the dog 52, acting, revolves the friction or guide rollers 45 and 46 sufficiently to force the solder upward beyond the ribs 54, to be again severed when the next load of cans has been placed upon the table and forced into position for soldering.

Having thus described my invention, I claim as new and desire to secure by Letters Patent—

1. In a can-capping machine, a soldering-iron comprising a tube having a tubular head on its lower end, and an annular solder-chamber extending from the top of the tube to the lower end of the head, substantially as set forth.
2. In a can-capping machine, the combination, with a tubular soldering-iron, of a tube concentrically located in the said iron, having a conical or flaring lower end, substantially as described, whereby a solder-passage is obtained, which is contracted at the bottom, as set forth.
3. In a can-capping machine, the combination, with a tubular soldering-iron and an inner concentric tube conical or flaring at its lower end, of a cap-clamping arm loosely fitted in said tube, substantially as shown and described.
4. In a can-capping machine, the combination, with a tubular soldering-iron provided with an inner concentric tube flaring or conical at its bottom, of a solder-carrier, a knife located between the solder-carrier and the soldering-iron, and means, substantially as described, for reciprocating the said knife and feeding the solder, as and for the purpose specified.
5. In a can-capping machine, the combination, with a revolute tubular soldering-iron provided with an interior concentric tubular solder-chamber extending throughout its length and contracted at the bottom, of a solder-carrier, guide-rollers adapted to convey the solder from the carrier to the upper end of the chamber of the soldering-iron, and a knife held to reciprocate between the guide-rollers and the soldering-iron, substantially as and for the purpose specified.
6. In a can-capping machine, the combination, with the soldering-irons thereof, of a gasoline-burner arranged at one side of the said irons, comprising a tube having peripheral perforations and provided with a mixing-chamber at its ends, a valved generating-tube, substantially as described, having its extremities spaced from and in alignment with the mixing-chambers, and a connection between the generating-tube and the gasoline tank or reservoir, substantially as shown and described.
7. In a can-capping machine, a tubular soldering-iron having a head at its lower end, an inner concentric tube extending through the

said iron from end to end, an annular solder-receiving space being formed between the tube and iron, and a vertically-movable cap-clamping arm extending down through and projecting below the lower end of said inner tube, substantially as set forth.

8. The combination of the rotary vertical tubular soldering-iron having a head at its lower end, an inner annular solder-chamber extending from end to end of the said iron, and a central vertically-movable capped clamping-iron with mechanism for automatically feeding solder to the upper end of said chamber, and a burner adjacent to the head of the iron for heating the same to fuse the solder as it passes down through the annular chamber, substantially as set forth.

9. The combination, with the frame, the vertical soldering-iron provided with an inner annular solder-chamber extending from its upper to its lower end or head, the central vertical cap-clamping rod, and the vertically-reciprocating can-holding table, of a solder-carrier on top of the frame, rolls for delivering the solder to the upper end of said annular chamber, a pawl-and-ratchet mechanism connected with said rolls and with the table for operating the rolls by the movement of the table, and a cutter between the rolls and the solder-chamber, substantially as set forth.

10. The combination, with the frame, the soldering-irons, mechanism for rotating them, the vertically-reciprocating table below the irons, and means for operating the table, of the feed-rolls operated by the upward movement of the table, the vertically-reciprocating cutter between the rolls and upper end of the soldering-iron, and connections between the vertically-reciprocating table and the cutter for raising it simultaneously with the rotation of the feed-rolls, substantially as set forth.

11. A can-capping mechanism consisting in the frame having a base 10, perpendicular end pieces 11, the horizontal connecting-braces 12 15 16, each having vertically-aligned parallel series of apertures, the apertured bars 20 above the brace 16, the rotary tubular soldering-irons mounted in the apertures of said braces and having connecting and operating gearing, the tubes 19, secured at their upper ends to the bars 20 and extending down into the soldering-irons to form the annular solder-chambers, the clamping-rods extending down through said tubes, the solder feeding and cutting mechanisms along opposite sides of the top brace 16, the vertically-reciprocating table on the base, power-connections between said table and the feeding and cutting mechanisms, and the longitudinal burner extending between the two series of soldering-irons, substantially as set forth.
